UNITED STATES PATENT OFFICE.

EGBERT G. SESSIONS, OF RICE, TEXAS.

CAR-COUPING.

SPECIFICATION forming part of Letters Patent No. 338,107, dated March 16, 1886.

Application filed January 9, 1886. Serial No. 188,131. (No model.)

To all whom it may concern:

Be it known that I, EGBERT G. SESSIONS, a citizen of the United States, residing at Rice, in the county of Navarro and State of Texas, have invented new and useful Improvements 5 in Car-Couplings, of which the following is a specification.

My invention relates to a car-coupling in which the opposite draw-heads are provided 10 with interlocking projections and connected by a horizontal pin or pins.

The invention consists in the construction and combination of parts hereinafter specified.

In the annexed drawings, Figure 1 is a plain 15 view of a car-coupling embodying my invention. Fig. 2 is a horizontal section of the same. Fig. 3 is a side view of the coupling. Fig. 4 is an end elevation of a box-car provided with my improved coupling attachments.

20 Referring to the drawings, the letter A designates a draw-head, with extension B and spring C at its rear end. Each draw-head is provided at one side with an end projection, D, which is rectangular in form. This rectangular projection D is provided near the body 25 of the draw-head with a horizontally-elongated opening or passage, E, and near its outer end said projection has a vertical slot, F, the walls of said slots being rounded internally, as shown 30 in Fig. 3. The outer end of each draw-head also carries a wedge-shaped projection, G, which has a horizontally-elongated slot, E', through its enlarged end, and a vertical slot, F', through its small end, the interior of said 35 slots or openings being rounded. The wedge-shaped projection G has a horizontal top and bottom surface. One side is parallel with the side of the rectangular projection, and its other side is inclined forward. This wedge-shaped 40 projection G is located near one side of the draw-head, opposite to and in line with the rectangular projection D, which is preferably located directly on the other side edge of the draw-head.

The coupling-pins H H are passed horizontally 45 through the interlocking projections D and G from opposite sides of the draw-heads, each pin being engaged in the horizontal slots

E E' in the projections of one draw-head, and in the vertical slots F F' in the projections of the opposite draw-head. It will be observed 50 that the close engagement of each horizontal coupling-pin at two points in the draw-head to which it is attached secures a firm and steady draft, while the loose or flexible engagement of said pins with the opposite draw-heads enables the cars to turn curves readily without 55 liability of derailment. By means of the vertical slots F F' in the ends of the projections D and G an up-and-down motion is permitted to the pin H, held in the horizontal slots E E' 60 of the opposite draw-head. This coupling is therefore adapted to connect cars having draw-heads of different heights, as well as those that are arranged on a level. Each coupling-pin H is carried at the lower end of a vertical rod, K, that is pivoted at L to the end of 65 a freight-car or to a convenient point on the platform of a passenger-car. In order to hold the rod or lever K in any desired position, 70 racks m m are provided, with which said rod or lever can be engaged. This rod or lever K may extend to the top of a freight-car and the racks m be located upon the top of the car, as shown in Fig. 4.

It will be seen that with this construction 75 and arrangement of devices cars of the same or different heights can be easily and quickly coupled and uncoupled either from the top or platform of a car, or from either side, without any risk of injury to the attendant.

80 What I claim as my invention is--

The combination, with the draw-heads provided with projections D and G, each having at its inner portion a horizontally-elongated slot, and at its outer portion a vertically-elongated slot, of the horizontally-slidable coupling-pins H H, for respectively engaging the said slots, substantially as described.

In testimony whereof I affix my signature in presence of two witnesses.

EGBERT G. SESSIONS.
